UNITED STATES PATENT OFFICE.

CHARLES McCLENNY, OF LOWELL, ARIZONA.

OPEN-TYPE FEED-WATER HEATER.

1,174,882.

Specification of Letters Patent. Patented Mar. 7, 1916.

Application filed April 20, 1914. Serial No. 833,205.

To all whom it may concern:

Be it known that I, CHARLES McCLENNY, a citizen of the United States, residing at Lowell, in the county of Cochise and State of Arizona, have invented certain new and useful Improvements in Open-Type Feed-Water Heaters; and I do declare the following to be a full, clear, and exact description of the invention, such as will enable others skilled in the art to which it appertains to make and use the same.

My invention relates to improvements in feed water heaters employing the exhaust steam from an engine for the purpose of supplying the heat for raising the temperature of the water to be fed to the boiler.

I am aware that various devices of this character have heretofore been patented and manufactured. Practical experience, however, proves that the majority of heaters of this type, are impractical in certain details.

The primary object of my invention, therefore is to improve the construction of open type feed water heaters to such an extent as to render them simple and inexpensive in construction and highly efficient in operation.

In carrying out the above end, I provide an upright tank, a transverse diaphragm therein, a water spray nozzle above the diaphragm and a steam inlet below the same.

A secondary object of my invention is to so construct and position the diaphragm as to cause the same to readily heat any water which may collect thereon.

Still another object of the invention is to provide simple and efficient means for automatically controlling the level of heated water within the tank.

A still further object of the invention is to provide means whereby the surplus steam, escaping from the heating tank, will be partially condensed.

With the above objects in view, the invention resides in certain novel features of construction and combination herein described and claimed and shown in the drawings wherein:

Figure 1 is a vertical sectional view of my improved feed water heater; Fig. 2 is a horizontal section on the line 2—2 of Fig. 1; and Fig. 3 is a detail horizontal section on the line 3—3 of Fig. 1.

In the accompanying drawings, I have shown my improved feed water heater as

comprising in general, an upright tank 1, a transversely disposed diaphragm 2 in said tank, a water spray nozzle 3 above the diaphragm, a steam inlet 4 below the diaphragm, a surplus steam outlet 5, a number of inclined baffle plates 6 therein, and means for automatically regulating the amount of water discharged from said nozzle, and consequently, the level of water 65 within the heater.

The tank 1 is preferably of cylindrical formation and may be constructed in any suitable manner, a plurality of sections of boiler plate being preferably employed. 70 The lower end of the tank 1 is provided with a funnel-shaped bottom 7, said bottom having a discharge opening which establishes communication between the interior of the tank 1 and a valved drain pipe 75 8. The upper end of the tank 1 is closed by a substantially cone-shaped top 9, the surplus steam outlet pipe 5 rising from said top and being provided, as before stated, with the baffle plates 6. The plates 6 are 80 preferably disposed as shown in Fig. 1, the inner edges of one vertical series projecting between the inner edges of the other series. By this positioning of the plates 6, an appreciable amount of the steam exhausted 85 through the pipe 5, will be trapped and, therefore, condensed into water.

The diaphragm 2 is perforated throughout its area and is provided on its periphery, with a depending flange 10 which is 90 secured by means of rivets 11 to the wall of the tank 1. As clearly shown in Fig. 1, the diaphragm 2 is disposed directly above the steam inlet 4, this positioning being found most advantageous by practical experiment.

The water spray nozzle 3 is preferably carried by an elbow 12 which curves downwardly from a feed water pipe 13, the latter projecting through one side of the tank 100 1 and having a water controlling valve 14 which is substantially in the form of a globe valve, the main difference being that the conical valve 15 moves toward the pressure when opening.

For the purpose of automatically operating the valve 15, I provide said valve with a depending stem 16, which projects slidably through a stuffing box carried by the casing 14, said stem being pivotally connected at its lower end to a transversely disposed lever 17 which is pivoted, inter-

mediate its ends, to an arm 18 which depends from the pipe 13. Pivotaly connected to the free end of the lever 17, is an adjustable link or rod 19, which projects 5 into a float receptacle 20, and is connected to a float 21, the area of the lower end of said float being approximately the same as the area of the bottom of the receptacle 20, which receptacle is in communication with 10 the interior of the tank 1, by means of a pipe 22, said pipe entering the tank near its lower end.

I have provided the baffle plates 6 for the purpose of retaining a great deal of 15 water which would otherwise escape, thus economizing to an appreciable extent. For the purpose of further economizing, in the amount of water, I provide the pipe 13 with a branch pipe 23 which leads from said 20 pipe, through the wall of the tank 1 and is connected to any one or a number of traps from which water of condensation may be supplied. If, however, it is not necessary to employ the pipe 23, the same may 25 be closed by a suitable valve (not shown).

The operation of the device, when the pipe 13 is connected to a source of supply and the pipe 4 is connected to the exhaust port of the engine, is as follows: The tank 30 1 being entirely empty, will cause the float 21 to fall, thus opening the valve 15 and allowing water to be sprayed from the nozzle 3 upon the diaphragm 2. When now the engine is set in motion, the exhaust steam, 35 coming therefrom, will be forced through the pipe 4 beneath said diaphragm, thus raising the temperature thereof to a sufficient extent to effectually heat the water sprayed from said nozzle. It will be understood that the steam rises through the 40 perforations in the diaphragm 2 and mingles with the water sprayed from the nozzle 3. The surplus steam will now rise and, on account of the positioning of the baffle 45 plates 6, will be retarded in its escape, thus condensing an appreciable amount thereof into water, which water will now fall upon the diaphragm 2 and will be again heated, after which it will flow to the lower end 50 of the tank 1 to be employed as the supply for the boiler, an outlet pipe 24 leading from the interior of the tank for the purpose of conducting the heated water therefrom. As the water level within the tank 55 1 rises, the float 21 will, of course, rise thereby closing the valve 15 and preventing the inward flow of water. When, however, the level within the tank falls, the valve 15 will

again open and more water will be discharged through the nozzle 3. For the 60 purpose of preventing the water level within the tank 1, from rising above a predetermined point, I provide an overflow pipe 25 which is disposed slightly beneath the steam inlet 4. The tank 1 is further provided with 65 a water gage 26 and with a manhole 27, closed normally by a metal plate 28.

From the foregoing description, taken in connection with the accompanying drawings, it will be readily seen that I have produced a comparatively simple feed water heater which will be highly efficient in operation and which will be inexpensive in construction.

Although I have described my invention 75 with considerable minuteness as to arrangement and form of parts, I do not wish to be limited to details of construction, arrangement of parts or character of materials, otherwise than as set forth in the 80 appended claim.

Having thus described my invention, what I claim as new and desire to secure by Letters Patent is:

A feed water heater comprising an upright cylindrical casing having a cone-shaped top and an inverted cone-shaped bottom, a valved drain pipe in the apex of said cone-shaped bottom, a steam outlet pipe secured in the apex of the cone-shaped top, 90 baffle plates formed in said outlet pipe, a perforated diaphragm secured midway the ends of said cylindrical casing, a water inlet pipe extending through the casing above the diaphragm and having a spray nozzle 95 on its inner end, and a cutoff valve located on the exterior of the casing, an upright float tank adjacent the lower end of the casing, a pipe leading from said tank to said lower end of the casing, a float in said 100 tank, connections between the float and the valve for closing the latter when the former is raised, a branch water inlet pipe extending through said casing, a steam inlet pipe into the casing below the diaphragm and 105 above the pipe leading to the tank, and a hot water outlet from said casing below the steam inlet.

In testimony whereof I have hereunto set my hand in presence of two subscribing 110 witnesses.

CHARLES McCLENNY.
